CLAIM

The ornamental design for the water box for pre-pasted wallpaper, as shown and described.

DESCRIPTION

FIG. 1 is a front elevational view of the water box for pre-pasted wallpaper showing my new design;

FIG. 2 is a rear elevational view thereof;

FIG. 3 is a left side elevational view thereof;

FIG. 4 is a right side elevational view thereof;

FIG. 5 is a top plan view thereof; and

FIG. 6 is a bottom plan view thereof;

FIG. 7 is a cross-sectional view thereof taken in a central elevational plane of FIG. 1; and,

FIG. 8 is an upper left side perspective view thereof.
